UNITED STATES PATENT OFFICE.

JOHN F. METTEN, OF PHILADELPHIA, PENNSYLVANIA, ASSIGNOR TO THE WILLIAM CRAMP & SONS SHIP & ENGINE BUILDING COMPANY, A CORPORATION OF PENNSYLVANIA.

REDUCTION-GEAR FOR MARINE STEAM-TURBINES.

1,234,194.

Specification of Letters Patent.

Patented July 24, 1917.

Application filed November 14, 1916. Serial No. 131,210.

To all whom it may concern:

Be it known that I, JOHN F. METTEN, a citizen of the United States, residing at Philadelphia, in the county of Philadelphia and State of Pennsylvania, have invented certain new and useful Improvements in Reduction - Gears for Marine Steam - Turbines, of which the following is a specification.

10 This invention relates to reduction gear mechanism and particularly to such mechanism for use between marine steam turbines and the propeller shaft which they drive. It is especially applicable to war vessels of 15 high power wherein it is desirable to keep the power per pinion as low as possible.

The object of the invention is to provide a gear casing which may be rigid with the turbine casings, thus joining all the elements 20 of the propeller drive into one unitary construction. It is also an object of the invention to provide a novel arrangement of pinion bearings and means for supporting them so that there will be ample bearing surface 25 and enabling each of the driving pinions to be readily accessible and removable without interfering with the operation of the others.

In one arrangement specifically shown 30 herein, high and low pressure turbines in steam series are located forward of the gear casing and each driving a pinion, the pinions meshing with a gear on the propeller shaft. A similar arrangement of turbines 35 is located aft of the gear casing driving two other pinions.

In the accompanying drawings,

Figure 1 is a plan view of an installation embodying this invention;

40 Fig. 2 is a view in side elevation;

Fig. 3 is a section on the line 3—3 of Figs. 1 and 2;

Fig. 4 is a section on the line 4—4 of Figs. 1 and 2;

45 Fig. 5 is an end elevation of the gear box; and

Fig. 6 is a section on the line 6—6 of Fig. 4.

In the embodiment of the invention 50 shown, the pinions 1, 2, 3, 4 mesh with a common gear 5 connected through flange coupling 6 to the propeller shaft 6'. Pinions 1 and 2 are driven respectively by high and low pressure turbines 1' and 2' in steam

series attached to the forward end of the 55 gear box 7 through intermediate boxes 8 and 9. Similarly pinions 3 and 4 are driven by high and low pressure turbines 3' and 4' attached to the after end of the gear box 7 through intermediate boxes 10 and 11. 60 These intermediate boxes 8, 9, 10 and 11 are bolted to the gear box and are provided with flanges 12 for bolting to the turbine casings.

In the apparatus shown, the pinions are 65 all of the same size and interchangeable, but may be of different sizes to suit any particular requirement of turbines. The pinions have separated tooth sections and between the sections are provided with center bearings (see Fig. 3). These bearings are carried on a yoke 13 cast integral with the gear box 7 and passing between the forward and after sections of the gear wheel 5 and beneath the flange connection 14 between 70 said gear wheel sections, end bearings of the pinions are supported in end walls 15 and 16 also cast integral with the gear case. The end bearings for the gear wheel 5 are additionally strengthened by 75 end covers 18 at either end which tie the end walls 15 and 16 together and the entire gear box is provided with a cover plate 19 fastened rigidly in place to act as a stiffener. 80

Along the lower part of each side the 85 gear box is formed of a hollow box-like construction 7' (see Figs. 3 and 4) to additionally strengthen the constructions. These reinforcing and stiffening means provide a gear box which with a minimum of material 90 is strong enough to act as a center nucleus for the turbine units attached to it through boxes 8, 9, 10 and 11. All the driving elements for a single shaft are thereby bound together in one unitary construction. The 95 various parts are firmly bound in fixed relation and do not shift or cant out of alignment as is often the case where the different parts of the drive are separately mounted.

The pinion center caps 20, 21 and the end 100 caps 22, 22 and 23, 23 can be removed independently for getting to the bearing brasses 20', 21', 22', 23', which are split horizontally. Pinion covers 24, 25 are also independently removable for inspection of 105 the pinions. Any one of the four pinions can be taken out without interfering with the others. The exposed caps of the center

bearings are advantageous in permitting the bearing temperatures to be readily determined by feeling, which is not the case in the usual two pinion design. The main gear bearings are accessible in the usual way by having caps 26, 27 removable independently of the end covers.

In the construction shown the driving pinions are supported in the middle as well as at their ends and ample and well distributed bearing surface is thus provided. The reinforcing and stiffening web used to support the central pinion bearings is also advantageous in further strengthening the entire gear box to serve as a center of attachment for the turbine casings. The removable stay bolt lends to the construction all the advantages of a completely closed center web and at the same time permits the ready insertion and removal of the main gear 5 by simply removing end plates 18 and bearing caps 26 and disconnecting the propeller coupling. The pinion mountings between recesses in the gear box and the caps 20 to 25 render the pinions and their bearings readily accessible for inspection and repair and any pinion may be removed without interfering with the other pinion in any way. The various elements of the whole installation are fitted and coöperate together to form a solid compact structure serving as a center of attachment for the driving units and rendering all parts of the apparatus readily accessible and removable. In arranging the pinions from the fore and aft turbines to overlap instead of being end for end, the construction is rendered more compact with a longitudinal saving of space equal to the length of one pinion. Since each set of turbines has its pinions on a common diameter through the center of the gear 5, either the forward or after set can be cut out at lower powers and still give a completely balanced drive.

It is apparent that a different arrangement of the driving units may be resorted to. For instance, 1' and 2' can be high pressure turbines, respectively, connected in series to 3' and 4' and either set may be cut out and a balanced drive produced. It is also evident that a different size or proportioning of parts may be used to accommodate the installation to the varying demands of service. The invention is not confined to the particular embodiment shown and described, but is intended to include such modifications thereof as fall within the scope of the appended claims.

Having thus described my invention, I declare that what I claim as new and desire to secure by Letters Patent is:

1. In a reduction gear for marine turbine installation, a four pinion arrangement having two of the pinions driven by turbines located on forward side of gear casing and

two driven by turbines located on after side of said gear casing, said pinions being removable, independently of their driving units.

2. In a reduction gear for marine turbine installation, four pinions symmetrically arranged and near the horizontal axis with their center bearings carried on a yoke formed in the gear casing, removable stay means, and end bearings carried in the end walls of the gear casing.

3. A reduction gear for marine purposes having four pinions, two of which are driven by high and low pressure turbines on forward side, and two by high and low pressure turbines on after side of gear case and separate boxes for connecting said turbines to said gear casing.

4. In a marine turbine installation, the combination with a reduction gear, of a plurality of driving units geared thereto, each unit having a separate pinion, and bearings for said pinions rendering each of them independently removable.

5. In a marine turbine installation, the combination with a gear box, of driving turbines forward and aft of said gear case, removable bearings fastened to each side of said gear case for removably supporting the driving pinions, and a gear intermediate of said box driven by said pinions.

6. In a marine turbine installation, the combination with a gear case, of driving turbines forward and aft of said gear case, a gear and driving pinions separated into separate toothed sections, and bearings for said pinions between said sections.

7. In a marine turbine installation, the combination with a gear case, of driving turbines forward and aft of said gear case, a gear and driving pinions separated into separate toothed sections, bearings for said pinions between said sections, and a transverse stiffening web supporting said bearings between said sections.

8. In a marine turbine installation, a reduction gear mechanism comprising a gear case, driving turbines forward and aft thereof, bearings carried by the sides of said gear case for removably supporting the driving pinions, and removable bearings carried by the ends of said gear case for removably supporting the propeller shaft gear.

9. In a marine turbine installation, the combination with a gear case, driving turbines forward and aft thereof, end and center bearings carried by said gear case for the driving pinions, a transverse stiffening web integral with said case and supporting said center bearings, a gear within said box, said web constituting a yoke encircling the propeller shaft gear.

10. In a marine turbine installation, the combination with a gear case, of turbines forward and aft of said gear case, and means

rigidly fastening the casings of said turbines to said gear case to form one unitary construction.

11. In a marine turbine installation, a reduction gear box having longitudinal stiffening means, driving turbines forward and aft of said gear case, and intermediate connecting boxes fastened to said gear case and to the casings of said turbines to produce a rigid unitary construction.

12. In a marine turbine installation, the combination with a gear case, of turbines located forward and aft of said case, pinions driven by said turbines, bearings for said pinions in the ends of said gear case, and special bearings for said pinions intermediate the ends of said gear case.

13. In a marine turbine installation, a reduction gear box having end bearings for the driving pinions, and an intermediate stiffening web supporting middle bearings for said pinions.

14. In a reduction gear mechanism for a marine turbine installation, a gear case having recesses on its side for supporting pinion bearings, and removable caps holding said pinions in said bearings and fastened to the sides of said case.

15. In a reduction gear mechanism for a marine turbine installation, a gear case having end bearings in its end walls integral with said gear case, and center pinion bear-

ings supported by a transverse yoke cast integral with said gear case.

16. A reduction gear case for a marine 35 turbine installation comprising end walls carrying bearings, and an intermediate stiffening web cast integral with said box and carrying center bearings.

17. A reduction gear case for a marine 40 turbine installation comprising end walls, longitudinal stiffening means for the side walls, and an intermediate stiffening web cast integral with the gear case.

18. A reduction gear case for a marine 45 turbine installation comprising end walls, longitudinal stiffening means for the side walls, a central stiffening web, and bearings on the sides of said gear case supported by said end walls and said central stiffening 50 web.

19. A reduction gear case for a marine turbine installation comprising end walls and side walls, longitudinal stiffening means for said side walls, and separate boxes at 55 the ends of said stiffening means for connecting the driving turbine casings to said gear case.

20. In a marine turbine installation, the combination with a main propeller shaft 60 gear of turbine driving units on different levels forward of said gear and turbine driving units on different levels aft of said gear.
